CLAIM

The ornamental design for a stand for tablet computer, as shown and described.

DESCRIPTION

FIG. 1 is a front, top, and right side perspective view of a stand for tablet computer, showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a rear, top, and right side perspective view thereof in a state that a front plate is rotated.
